US00D721539S

(12) **United States Design Patent**
Johnson(10) **Patent No.:** **US D721,539 S**
(45) **Date of Patent:** **** Jan. 27, 2015**(54) **TUBULAR SMOKER DEVICE**

(71) Applicant: **Todd Johnson**, Savage, MN (US)
 (72) Inventor: **Todd Johnson**, Savage, MN (US)
 (***) Term: **14 Years**
 (21) Appl. No.: **29/444,857**
 (22) Filed: **Feb. 5, 2013**
 (51) LOC (10) Cl. **07-02**
 (52) U.S. Cl. **USPC D7/409**
